UNITED STATES PATENT OFFICE.

GEORGES FRANÇOIS DUPONT, OF PARIS, FRANCE, ASSIGNOR TO PIERRE GERMAIN, OF FONTENAY-AUX-ROSES, FRANCE.

MICROPHONIC TRANSMITTER.

SPECIFICATION forming part of Letters Patent No. 643,484, dated February 13, 1900.

Application filed April 1, 1898. Serial No. 676,108. (No model.)

To all whom it may concern:

Be it known that I, GEORGES FRANÇOIS DUPONT, a citizen of the Republic of France, and a resident of Paris, France, have invented certain new and useful Improvements in Microphonic Transmitters, of which the following is a full, clear, and exact description.

This invention relates to a microphonic transmitter which is adapted to work with high-voltage currents.

In the accompanying drawings, Figure 1 is a vertical section of a transmitter constructed according to my invention. Fig. 1^a is a face view of one of the carbon disks. Figs. 2 and 2^a are views of a transmitter having a plurality of diaphragms, and Fig. 3 is an enlarged sectional view of one of the microphones shown in Fig. 2.

Referring to Fig. 1, the transmitter consists of two circular disks A A', of carbon baked or heated to 3,500° centigrade and provided with pyramidal projections on the active or working surface *a*. These disks are electrically covered with metal over their outer or inactive surfaces *a'*. This operation should be effected in such manner that the deposited metal thoroughly enters or deeply penetrates into the carbon of the disks to reduce to a minimum their electrical resistance. By using carbon of suitable porosity this result is attained. A ring *a'* is arranged around the two disks, and the space between the walls of this ring is subdivided by thin walls of mica or other insulating material into a number of cells *a*² of equal surface, which are filled with granulated carbon heated or baked at a very high temperature. The microphone is thus divided into a number of small similar microphones between the two disks. In the type shown in the drawings there are eight compartments.

While one of the disks, A, is secured to the ring *a'*, the other, A', is movable on its axis *x x*. The movable disk is secured to a rigid aluminium cross *a*³, having four arms. These arms serve to secure on one side four small spiral springs *a*⁴, fixed to the other side by four aluminium hooks fixed to or solid with the ring and the disk A.

In the several cavities or recesses formed by the mica walls I place the same quantity,

by volume and weight, of granulated carbon, the grains being of similar shape and size, and I provide springs of equal tension, so that the mounting or setting up of the microphone 55 is effected without further adjustment.

I provide leading-in wires of refined copper twisted together and covered with a coating of calcareous silicate base, which diminishes metallic vibrations and retains indefinitely 60 its properties in spite of the eventual action of heat. These wires are joined to the disks, each of which has at the center a projecting cylindrical shoulder *a*⁵. In the middle of this shoulder is formed a hole into which is 65 fixed a screw. One of these screws serves to connect the microphone to the vibrating membrane B, which is thus the sole support of the disks and interposed granulate.

By suitably regulating the microphonic current a slight heating takes place within the mass of the granulate, which should scarcely exceed 35° centigrade. This small amount of heat developed has a doubly-favorable effect without altering the properties of the substances forming the microphone. In the first place the active resistance is reduced to a minimum with the minimum of dead-weight. In the second place the heating removes dampness, so harmful to microphonic effects. To aid in this removal of dampness, small holes are formed in the ring *a'*. To maintain a perfect state of dryness of the air surrounding the active granulate is so important that to thoroughly effect it I place in the compartment in which the microphone is mounted a small desiccating-tube. This tube can be of any desired shape. It can be made of canvas or linen perforated in places and filled with a fine beaten powder of absorbent cellulose and dry magnesium chlorid or with any other similar substance. The proportion, by volume, of these two products should be such that the whole of the magnesium chlorid can deliquesce without a drop of liquid oozing 95 out of the perforated tube.

In the modification shown in Figs. 2, 2^a, and 3 the vibrating plate of the transmitter includes a certain number of similar diaphragms R of special glass, having a thickness of from 100 twelve to eighteen hundredths of a millimeter and a diameter of from six to eight centi-

meters. In front of each vibrating diaphragm is a rigid wall r , having the form of the hermetical cover, Fig. 2, or constituting an air-chamber furnished with a small opening r' , Fig. 3, for the escape of damp air and condensed water. The various air-chambers of the same apparatus communicate through tubes s with a single opening S , to which is secured the mouthpiece.

10 In Fig. 3 I have shown an elastic tube of thin soft india-rubber t in place of the mica ring of Fig. 1, and it has openings t^3 . Around the rubber ring a light wire t' is specially wound to close the openings sufficiently to prevent the fine granulate from passing out, without, however, reducing the elasticity of the whole.

15 The object of the subdivision of the microphone into a certain number of similar and separate parts is to reduce the sparking due to excess in voltage without necessitating undue compression of the granulate, which would greatly reduce the sensitiveness of the microphone.

20 25 I prefer to change the polarity of the microphonic current at intervals of twenty-four hours or at the end of a conversation, as it is conducive to the preservation of the granulate of the microphone, especially where there are high currents, such as used in my system of microphone.

I may modify the details of construction of

my improved microphonic transmitter without departing from the spirit of my invention.

I claim as my invention—

35 1. A microphone consisting of carbon disks, a plurality of cells between them, granulated carbon in said cells and springs adapted to hold the disks together, in combination with a vibrating member, to which said disks are 40 attached and by which they are solely carried, substantially as described.

2. A microphone consisting of a pair of carbon disks, elastic tubing of less length than the diameter of the disks connecting said disks 45 and granulated carbon between them, in combination with springs to hold the disks together and a vibrating membrane to which said disks are attached and by which they are solely supported, substantially as described. 50

3. A microphone consisting of a pair of carbon disks, elastic tubing connecting them, granulated carbon between them, openings in said tubing, and wire around said tubing partially closing the openings to prevent the 55 granulate from escaping, substantially as described.

In testimony whereof I have signed my name to this specification in the presence of two subscribing witnesses.

GEORGES FRANÇOIS DUPONT.
